CLAIM

The ornamental design for a divided tray for card games, as shown.

DESCRIPTION

FIG. 1 is a front elevation of a divided tray for card games showing my new design;

FIG. 2 is a rear elevation thereof;

FIG. 3 is a top plan view, the bottom plan view being a mirror image thereof;

FIG. 4 is a left side elevation, the right side elevation being a mirror image thereof; and

FIG. 5 is a cross-section taken along line 5—5 of FIG. 1.
